STOKER PIPE

Harold T. Blum, Glenmont, Ohio, assignor to
 Briar Hill Corporation, Millersburg, Ohio, a
 corporation of Ohio

Application August 1, 1939, Serial No. 287,841

3 Claims. (Cl. 131—181)

The present invention relates to tobacco smoking pipes and is an improvement in smoking pipes wherein the firing of the tobacco being consumed can be manually controlled.

5 The principal object of the present invention is to provide a smoking pipe having means therein for controlling the firing of the tobacco, which pipe is capable of cooling the smoke thus produced, thereby condensing moistures, oils and heavy tars therefrom and which entire pipe structure can be economically produced.

10 A further object of the present invention is to provide a smoking pipe structure wherein the tobacco is consumed in one portion thereof, 15 while the remaining portions of the structure remain relatively cool and provide passageways whereby the smoke produced may readily contact the relatively cooled portions for cooling the smoke and condensing objectionable ingredients therefrom.

20 An equally important object of the present invention is to provide a smoking pipe structure having means incorporated therein for controlling the firing of the tobacco being consumed and maintaining the burning portion of the tobacco 25 within a heat-retaining chamber which is insulated from the remaining portions of the pipe structure and which pipe structure can be quickly and simply dismantled whereby all of the elements comprising the same can be easily and quickly cleansed from time to time.

25 And a still further and equally important object of the present invention is to provide a pipe structure having a tobacco stoking means incorporated therein, a tobacco reservoir and a heat-insulating chamber, all of which can be quickly assembled or disassembled as desired and when assembled, will automatically correctly position themselves whereby the pipe may function correctly.

30 Further objects of the present invention will in part be pointed out in the following detailed description of the accompanying drawing and will be in part obvious from a consideration thereof.

35 In the drawing:

Fig. 1 is a side cross sectional view of the pipe structure according to the present invention.

Fig. 2 is an end view of the pipe structure taken 40 on line 2—2 of Fig. 1.

Fig. 3 is a top cross sectional view of the bowl portion of the present smoking pipe taken on line 3—3 of Fig. 1.

Fig. 4 is an enlarged side cross sectional detail 45 view of a portion of the pipe structure, and

Fig. 5 is a side cross sectional view of a tubular member forming the tobacco reservoir and which forms an element of the present pipe structure.

Referring now more particularly to the accompanying drawing wherein like and corresponding parts are designated by similar reference characters, numeral 1 refers to the side wall of the pipe bowl having a base 2 closing one end thereof. Base 2 has centrally located opening 3 formed therethrough and which opening 3 is stepped, 10 whereby the upper portion thereof forms a recess 4 in the interior face of base 2. The opposite or open end 5 of bowl 1 projects inwardly and provides a threaded bore therein. Portion 6 of bowl 1 has formed extending therefrom a tubular 15 stem 8 having a bore 9. Said bore 9 is connected with the interior of bowl 1 through a series of openings formed in the upper part of portion 6. The usual smoking pipe mouthpiece 10 having a bore 11 is connected to and closes the open end 20 of stem 8.

Bowl 1 with base 2 and stem 8 extending therefrom are formed from a lightweight metal such as, for example, aluminum or magnesium and in the formation thereof, are cast as one piece with 25 openings 1 being subsequently formed through portion 6 by boring or other suitable operation. Producing these members in this manner materially reduces the cost thereof and, at the same time, produces members capable of readily receiving the remaining elements for functioning 30 in the manner desired, as will be hereinafter more fully pointed out.

Positioned within bowl 1 is a tubular tobacco reservoir 12 having an annular flange 13 formed 35 extending from the upper end thereof and a second annular flange 14 formed extending from the lower or opposite end thereof and which is seated upon the interior face of base 2. Reservoir 12 has an octagonal cross sectional configuration which is formed by a series of longitudinally extending and angularly related side walls 15. The upper end of reservoir 12 has an annular series of openings 16 formed extending from the upper interior edge of reservoir 12 40 downwardly therethrough to a point adjacent the lower face of flange 13. Reservoir 12 with its annular flanges 13 and 14 are formed as one piece from a heat-conducting material such as a lightweight metal as, for example, aluminum 45 or magnesium.

Seated upon the upper face of flange 13 is the lower face of a heat-insulating tubular ring 17 whose lower peripheral portion is stepped and threaded for being detachably positioned within 50

the threaded bore of portion 5 of bowl 1. The ring 17, which is formed from a heat-insulating material such as meerschaum or brierwood, has a centrally located opening 19 formed therethrough and which opening is formed of a series of angularly related walls which extend contiguous from walls 15 of reservoir 12 when ring 17 is screwed tightly against flange 13.

Rotatably mounted within opening 3 is a cylindrically-shaped control and elevating member 20, which member has a threaded bore 22 formed through the head thereof and a chamber 23 formed extending from said head. Said elevating member 20 has a laterally extending annular flange 21 which is rotatably seated within recess 4 and thereby rotatably supports member 20 longitudinally of opening 3. Flange 21 has a slightly larger diameter than the diameter of the bore of reservoir 12 and the lower face of flange 14 slidably contacts the upper face of flange 21 for retaining the flange within recess 4, while at the same time permitting the free rotation thereof.

A threaded rod 24 having a stop 25 formed at one end thereof is rotatably mounted within and extends through chamber 23 and bore 22 and threadedly engages the threads of said bore 22.

A tobacco-supporting disc 27 having an octagonal periphery is positioned laterally of the bore of reservoir 12 with the periphery thereof in slidable contact longitudinally of the walls 15 but having the diameter of disc 27 substantially equal to the diameter of the bore of reservoir 12, whereby the periphery of disc 27 is in a socket-like engagement with walls 15, thereby preventing the rotation of disc 27 laterally of reservoir 12. Said disc 27 has a rectangular opening formed centrally thereof and in which is positioned a similarly shaped upper end 26 of rod 24 and which end 26 is securely fastened to disc 27 by flattening the top portion thereof.

The elements forming the present pipe structure are assembled after the tobacco-elevating members comprising control member 20, rod 24 and disc 27 are assembled. Rod 24 is inserted through the open end of chamber 23 within bore 22 through which it is screwed, at which time disc 27 is mounted upon end 26 and securely fastened thereto. These assembled members are inserted within bowl 1 with control member 20 extending through opening 3 and flange 21 seated within recess 4. Reservoir 12 is inserted within said bowl 1 with flange 14 seated upon the interior face of base 2 and the outer portion of the upper face of flange 21. The bore of reservoir 12 will have inserted therein disc 27. Opening 3 and recess 4 will center control member 20 relative to bowl 1 and reservoir 12 will be similarly centered due to flange 14 contacting the lower interior face of bowl 1. Upon ring 17 being screwed within portion 5 of bowl 1, the lower face thereof will contact the upper face of flange 13 and force reservoir 12 downwardly, whereby flange 14 will be sealed against the interior face of base 2 and flange 21 will be rotatably locked in position. Similarly, the upper face of flange 13 will be sealed against the lower face of ring 17 with the bore of reservoir 12 having the opening 19 of ring 17 extending contiguous therewith. A reversal of the foregoing assembling steps permits the pipe structure to be as readily and easily disassembled, whereby each element thereof can be readily cleansed in any manner desired without any inaccessible portions remaining which would

hinder in a thorough cleansing of all of the elements.

After the pipe structure has been assembled, tobacco is placed through opening 19 within the bore of reservoir 12 and upon the upper face of disc 27, the upper portion of the tobacco being positioned within opening 19. Upon a flame being applied to the upper portion of the tobacco within opening 19 and the smoker drawing upon bore 11, the tobacco will be ignited due to a draft passing through the pipe structure, as indicated by the arrows of Fig. 1 of the drawing.

As the tobacco is consumed, fresh tobacco is supplied to within opening 19 from the bore of reservoir 12 by the smoker imparting a right-hand rotation to control member 20, which causes threaded rod 24 to unscrew from within bore 22 due to the fixed connection of rod 24 with disc 27, which disc 27 is prevented from rotating by walls 15 of said reservoir. The unscrewing of rod 24 advances disc 27 upwardly within reservoir 12 and positions the tobacco mounted thereon. This advancing of disc 27 is continued from time to time in order to provide a fresh supply of tobacco within opening 19 and also to position the burning portion thereof at given points within said opening 19, which point depends upon the particular taste of the smoker. The closer the upper portion of the burning tobacco approaches the upper end of opening 19, the more air will be supplied thereto and it has been found that various smokers desire more or less air to be supplied to the tobacco than others, depending upon their particular taste.

The burning portion of the tobacco is maintained at all times within opening 19 and the smoke therefrom is drawn through openings 16 to within the space provided between the periphery of reservoir 12 and bowl 1 and passes therefrom through openings 7 to within bore 9 and from thence through bore 11 to the smoker. Ring 17 being formed of a heat-insulating material, the heat of combustion from the burning tobacco will be retained therein and not conducted to the adjacent members, bowl 1 and reservoir 12. As the smoke passes from openings 16, it will contact the relatively cool bowl 1 and reservoir 12 and will be cooled thereby. Further, bowl 1 and reservoir 12 being formed from a heat-conducting material will readily conduct heat from the smoke and the temperature, therefore, of the smoke will be appreciably lowered, whereby heavy oils, tars and moisture will be condensed therefrom and settle upon flange 14 and due to the positioning of openings 7, will not be permitted to pass with the smoke through said openings 7. Stem 8 being also formed from a heat-conducting material, will readily cause the smoke contacting the same to be further cooled, whereby additional oils, tars and moisture will be condensed therefrom. Also, bore 9 permits the smoke entering from openings 7 to expand and remain therein for being gradually drawn therefrom through the relatively smaller bore 11, whereby the smoke is given additional time to be further cooled.

Openings 16 of reservoir 12 will draw air through opening 19 along the walls of said opening and thereby will cause the tobacco within opening 19 to be completely consumed and, at the same time, guide the smoke from the burning tobacco away from the fresh tobacco in order that the same may not be contaminated or damped by the residue from the consumed portion of the tobacco.

The pipe structure as herein described and dis-

closed is capable of considerable modification and such modifications thereof as come within the scope of the accompanying claims are deemed to be a part of the present invention.

5. I claim:

1. An improvement in smoking pipes comprising a member forming a connected bowl and stem, and composed from heat-conducting material, said bowl having a stepped opening formed through the base thereof, telescopic extension means rotatably mounted through said opening, said telescopic means having a projection rotatably seated upon a portion of said stepped opening, a tube having a pair of annular flanges each formed extending from the peripheral ends thereof, a plate positioned within said tube and connected to said telescopic means, one of said flanges being seated upon the base of said bowl and slidably contacting said projection of said telescopic means for cooperating with said stepped opening for retaining said telescopic means longitudinally of said opening, a ring formed from heat-insulating material detachably mounted upon the open end of said bowl and the other of said flanges, the bore of said ring being connected to the bore of said tube, said tube having openings formed therethrough and one of said flanges contacting the side wall of said bowl for spacing said tube from said side wall.
2. An improvement in smoking pipes comprising a member forming a connected bowl and stem and composed from heat-conducting material, an opening formed through the base of said bowl, a recess formed in the interior face of said bowl about said opening, a tubular member having a threaded bore and rotatably mounted through said opening, said member having an annular flange slidably seated within said recess, a threaded rod extending through said member in threaded engagement therewith, a second tubular

member retaining said flange in said recess, said second tubular member and said bowl forming a passageway therebetween which communicates with said stem, a plate slidably positioned longitudinally of said second tubular member and connected to said rod, said plate and said second tubular member having such configuration as will prevent relative rotation therebetween, a heat-insulating member having an opening formed therethrough and mounted upon the open end of said bowl and having said opening extending contiguous from the bore of said tube and said tube having openings formed therethrough adjacent the bore of said insulating member.

3. An improvement in smoking pipes comprising a member formed from heat-conducting material and forming a connected bowl and stem, said bowl having an opening formed through the central portion of the base thereof, a centrally located recess formed in the interior face of said bowl base, an extension member rotatably mounted through said opening, a flange extending from said extension member slidably seated within said recess, a tube having a flange extending from the peripheral end portion thereof and slidably contacting the flange of said extension member for retaining the same in said recess, the flange of said tube being seated upon the interior face of the base portion of said bowl and contacting the side wall of said bowl for spacing said tube from said side wall, a tubular member of heat-insulating material detachably mounted upon the open end of said bowl and the opposite end of said tube, the bore of said tubular member extending contiguous from the bore of said tube, a disc mounted within said tube bore and connected to said extension member, and an annular series of openings formed through said tube adjacent said tubular member.

HAROLD T. BLUM. 40
